(57) **CLAIM**

The ornamental design for a mono-body type integrated function computer, as shown and described.

DESCRIPTION

FIG. 1 is a perspective view of a mono-type integrated function computer showing our new design;

FIG. 2 is another perspective view thereof without the keyboard;

FIG. 3 is a front elevational view thereof;

FIG. 4 is another front elevational view thereof with the keyboard;

FIG. 5 is a rear elevational view thereof;

FIG. 6 is another rear elevational view thereof;

FIG. 7 is a top plan view thereof;

FIG. 8 is another top plan view thereof with the keyboard;

FIG. 9 is a bottom plan view thereof;

FIG. 10 is a left side elevational view thereof;

FIG. 11 is a right side elevational view thereof; and,

FIG. 12 is a perspective view thereof.
